Primary Examiner — Samantha Wood(74) Attorney, Agent, or Firm — Lora J. Graentzdoerffer(57) CLAIM

The ornamental design for a freestanding tub filler, as shown and described.

DESCRIPTION

FIG. 1 is a perspective view of a freestanding tub filler showing our design;

FIG. 2 is a front elevational view;

FIG. 3 is a rear elevational view;

FIG. 4 is a side elevational view;

FIG. 5 is a side elevational view;

FIG. 6 is a top plan view; and,

FIG. 7 is a bottom plan view.

The broken lines are included for the purpose of illustrating portions of the freestanding tub filler and form no part of the claimed design.

1 Claim, 7 Drawing Sheets(56)
